HOLDING TRAY FOR TEST TUBES, VIALS, OR THE LIKE

Ronald W. Emmitt, 28367 Ridgebrook,
Farmington, Mich.

Filed Nov. 24, 1965, Ser. No. 88,202

Term of patent 14 years

(Cl. D16—1)

FIGURE 1 is a perspective view of a holding tray for test tubes, vials, or the like, showing my new design;

FIGURE 2 is an elevation view of an end thereof, as seen from line 2—2 of FIGURE 1;

FIGURE 3 is an elevation view of the other end thereof, as seen from line 3—3 of FIGURE 1;

FIGURE 4 is a front elevation view thereof, as seen from line 4—4 of FIGURE 2;

FIGURE 5 is a rear elevation view thereof, as seen from line 5—5 of FIGURE 2;

FIGURE 6 is a top plan view thereof, as seen from line 6—6 of FIGURE 3; and

FIGURE 7 is a bottom plan view thereof, as seen from line 7—7 of FIGURE 4.

I claim:

The ornamental design for a holding tray for test tubes, vials, or the like, as shown.
